(57) **CLAIM**

Jul. 28, 2006 (EM) 000566906-0001

The ornamental design for a speakerbox, as shown.

(51) **LOC (8) Cl.** **14-01**

DESCRIPTION

(52) **U.S. Cl.** **D14/211**

(58) **Field of Classification Search** D14/204,
D14/209-216; 181/143-144, 147-148, 150,
181/157, 198-199, 151, 153; 381/300-302,
381/306, 333, 345, 361-364, 386-388, 332,
381/336

FIG. 1 is a perspective view showing my design;

See application file for complete search history.

FIG. 2 is a front elevational view thereof;

FIG. 3 is a rear elevational view thereof;

FIG. 4 is a right side elevation thereof;

FIG. 5 is a left side elevational view thereof;

FIG. 6 is a top plan view thereof; and,

FIG. 7 is a bottom plan view thereof.
